ELECTRICAL INDICATING MEANS

Merton L. Haselton, Rye, N. Y., assignor, by
mesne assignments, to The Teleregister Cor-
poration, New York, N. Y., a corporation of
Delaware

Original application May 11, 1928, Serial No.
276,883. Divided and this application January
12, 1937, Serial No. 120,305

4 Claims. (Cl. 177—326)

- This invention relates to electrical indicating means. According to certain of its phases, although not limited thereto, the invention more specifically relates to electromagnetically driven 5 rotatable indicating devices adaptable to the posting of varying stock quotations or other information. Other phases of the invention relate to means for mounting such indicators and also electrical circuit connecting devices therefor. 10 The objects of this invention include the provision of apparatus and arrangements of the above indicated class which will be of a simple and durable construction and flexible in operation. 15 This application is a division of my copending application Serial No. 276,883, filed May 11, 1928, for Electrical indicating means, now Patent No. 2,067,187, issued January 12, 1937.
- Further and more specific objects, features and 20 advantages will more clearly appear from the detailed description given below taken in connection with the accompanying drawings which form a part of this specification.
- The invention consists in the novel features 25 of construction, arrangements, combinations of parts and electrical connections as hereinafter described, but by way of example only, as being illustrative of preferred embodiments of the invention.
- In the drawings, Fig. 1 is a front elevational 30 view showing one embodiment of the invention adaptable for use as a broker's automatic stock quotation indicating board. This figure shows a section, partly broken away of such a board with certain cover plates and electrical connections removed;

Fig. 2 is a sectional view taken substantially along the line 2—2 of Fig. 1;

Fig. 3 is a side elevational view of one form of 40 indicating unit adaptable to the construction shown in Fig. 1;

Fig. 4 is a top plan view partly broken away of the indicator unit of Fig. 3;

Fig. 5 is a transverse sectional view of Fig. 4;

Figs. 6 and 7 are enlarged detailed views illustrating the construction of a commutator which may be used in the device of Fig. 3;

Fig. 8 is a diagram showing the electrical connections for a broker's board as of Fig. 1;

Fig. 9 is a front view of a frame construction for carrying the broker's board sections as of Fig. 1.

The indicator unit as shown in Figs. 3-7 inclusive will first be described. The characters to be exhibited, such as price quotation digits, or let-

ters, may be arranged around the periphery of a rotatable drum member as at 20. For example, if digits are to be posted, numerals from 1-9, 0, and a blank or "normal" position space may be successively arranged around the periphery of this drum so that such numerals may be exhibited one at a time at the front of the indicator through an opening 21 when the drum is rotated.

A plurality of these indicator units may be 10 arranged side by side so that a group of the units, for example, will exhibit the various digits such as the hundreds, tens, units and fraction digits of a quotation. Also, when the invention is applied to brokers' boards, these units may be 15 arranged in pluralities of groups so that each group exhibits the quotations for one stock, and each sub-group may exhibit one individual quotation such as the "open", "high", "low" or "last" of a particular stock. This invention is particularly 20 adaptable to brokers' quotation boards or the like apparatus, such as shown in the copending application of Robert L. Daine and René Guyé, Ser. No. 246,474, filed January 13, 1928, now Patent No. 1,872,126, issued August 16, 1932. Also, if 25 desired, this invention is readily adaptable for use in apparatus embodying the invention of the patent of Robert L. Daine, No. 1,658,516, issued February 7, 1928. The indicators may be 30 controlled over circuit arrangements such as shown in the following copending applications: Merton L. Haselton, Ser. No. 244,873, filed January 6, 1928, now Patent No. 1,890,876, issued December 13, 1932; Merton L. Haselton, Ser. No. 248,069, filed January 20, 1928; Merton L. Haselton and 35 Page S. Haselton, Ser. No. 256,160, filed February 23, 1928, now Patent No. 1,890,878, issued December 13, 1932.

The indicator drums 20 may be rotated with a step-by-step movement, such movement in the 40 example shown being always in the same direction as indicated by the arrow in Fig. 4. The drum 20 may be mounted within a frame member 22. If desired, this frame member may be 45 formed of a single piece of suitable magnetic sheet material and extending from the top front portion 23 of the unit, thence along the top of the unit and downwardly as at 24 to form the rear of the unit and thence along the bottom of the unit as at 25.

Within the rear portion of this frame, an operating magnet as at 26 may be mounted in a horizontal position, the rear end of its pole piece being secured as by a screw 27 to the rear frame portion 24.

5

55

The magnet 26 is arranged to cooperate with an armature member 28, which may be provided with a pair of lugs as at 29 pivotally mounted upon a shaft 30, which is in turn affixed at its ends within the top and bottom frame portions 22 and 25. The armature may be normally held in its retracted position by a leaf spring as at 31 riveted as at 32 to the armature member at one end, its other end at 33 resting against a lug member 34 struck downwardly from the top frame portion 22 and integrally formed therewith.

The drum 20 may be mounted upon a shaft as at 35, which in turn is rotatably mounted at its ends within the top and bottom frame portions 22 and 25. The drum itself may comprise a cylindrical stamping of sheet metal having one end wall as at 36 clamped between a starwheel 37 and a washer member 38. The starwheel may be fixed against rotation in respect to the shaft 20 and the drum 20 may be riveted to the starwheel as shown, so as to also rotate with the shaft.

The starwheel 37 may be formed with a number of teeth equal to the number of characters or character spaces provided on the periphery of the drum (or an even multiple thereof), that is, in this instance, 11 in number. These teeth are designed to cooperate with an operating fork 39 which may be riveted as at 40 to the armature lug 29 so as to be movable in response to the operation of the armature 28. That is, the fork 39 oscillates about the pivoting shaft 30, together with the armature 28, when the magnet is impulsively energized. With the starwheel and fork of the particular shapes and relative dimensions substantially as shown, the same cooperate in a manner such that with each movement of the armature, the starwheel together with the drum member, is advanced always in the same direction through an angle subtended by the space between two teeth of the starwheel; that is, the drum is advanced one step each time that the magnet is energized by an electrical impulse. Thus, the drum is advanced through such an angle as to remove from exhibition one character and to exhibit the next succeeding numeral, character, or space. A desirable specific form of starwheel and fork construction is explained in further detail in the copending application of Ernest Frischknecht and Jean Abegglen, filed March 1, 1928, Ser. No. 258,219, now Patent No. 2,052,539, issued August 25, 1936. In the particular form of construction here shown, it will be observed that the fork arm 39a is caused to engage the starwheel when the fork is moved by the operation of the armature, whereas the longer fork arm 39b is caused to engage the starwheel when the retracting spring 31 comes into play. With the parts shaped substantially as shown, the fork arm 39a while being moved by the magnet is in actual working engagement with the starwheel teeth during the major portion of its movement, in this particular instance, during approximately 53% of the time of such movement, so that the work done by the magnet in opposing the spring 31 and in moving the drum is efficiently distributed over a considerable portion of the period of movement. On the other hand, the working portion of the stroke of the fork arm 39b as operated by the spring 31, need not necessarily comprise such a large percentage of the total stroke for the reason that the work to be done by the spring is less than required of the magnet. The spring merely has to move the drum and does not have to flex a retracting spring in addition, as is done by the force of the

magnet. In the particular construction illustrated, the actual working stroke of the fork arm 39b extends over approximately 42% of the total period of its stroke. That is, the fork arm 39b, under the influence of the spring 31, needs to be in actual working engagement with the starwheel during a relatively shorter portion of its period of movement.

It will also be observed that during the initial portion of the stroke of the fork, both when moved by the magnet and by the magnet and by the spring, the fork arms are free to acquire a considerable momentum before actually contacting with the starwheel so that the inertia of the drum is to a considerable extent overcome by the force of the impact of the fork arms against the starwheel teeth. Yet, it will be observed that the fork arm points, as well as the starwheel teeth, are so shaped that the impacts will take place between flat parallel surfaces of contact at the moments when the drum is started and when it is stopped. Also, the spring 31 being initially substantially straight, its tension during energization of the magnet will gradually increase from a very low value to its maximum value in a manner closely corresponding to the gradual increase of the electromotive force of the magnet as the armature approaches the pole piece. The starwheel and fork construction as illustrated represents a carefully adjusted balance of various mechanical factors and features including those above mentioned, in addition to others further explained and claimed in the patent to Ernest Frischknecht, et al., above referred to.

The magnet 26 may be energized in various ways, but according to the preferred embodiment of the invention, two different circuits are provided respectively for the "actuation" of the drum to exhibit a new quotation and for the "restoration" movement of the drum preparatory to the "actuation" thereof.

A commutator as at 41 mounted upon the drum shaft 35 may be provided to automatically connect and disconnect these circuits at the proper times. The constructional details of this commutator as shown in Figs. 6 and 7 will now be explained. A hub member 42 fixed to the shaft 35 as by a pin 43 comprises the supporting frame for the commutator parts and is also formed with a disc shaped contact portion 44. Another disc shaped contact member 45 may be secured to the member 44 as by screws 46 and insulated therefrom by an insulation piece 47. As shown in Fig. 7, a sector of the contact portion 44 may be cut away as at 48 and, within the space thus provided, a sector contact 49 may be inserted and secured in place and electrically connected to the contact 45 by rivets as at 50. Insulation as at 51 may be provided between the sector 49 and the contact portion 44.

A pair of spring brushes 52 and 53 are arranged to engage the opposite faces of the commutator 41. As indicated in Fig. 7, these brushes are preferably formed with bifurcated or double contact portions as at 54 and 55 to insure continuous contact at the desired times without danger of sparking. The brushes may be fixed to the lower frame portion 25 as by screws 56, which also serve to affix to the frame portion three connection or contact members 57, 58 and 59. The contact members 57 and 59 respectively are clamped flatwise against the brushes 52 and 53 in electrical contact therewith, but otherwise the brushes and contact members secured by the screws 56 may

be insulated from one another by layers of insulation as at 60. The top layer of insulation may be surmounted by a clamping piece 61. As shown in Fig. 3 the brushes 52 and 53 may preferably 5 extend substantially straight forwardly from their clamped areas to the commutator. With the brushes thus formed straight (except for their contacting tips) they may be readily standardized with a high degree of uniformity so as to 10 engage the commutator with the proper pressure with little or no adjustment after assembly of the device. The contact members 58 and 59 as shown may extend beneath the clamping means and thence a considerable distance toward the 15 commutator, as shown at 62, to provide protective means limiting the possible bending of the brushes and preventing the flexure of the brushes from being too concentrated at the clamping means. The contacts 57 and 58 as shown may 20 be connected respectively to the two ends of the magnet winding, while the contact 59 is connected to the brush 53. With these connections one end of the magnet winding may always be connected with an outside circuit through the 25 contact 58, while the other end of the magnet winding may be grounded through the commutator or alternately connected through the commutator to an outside circuit through contact 59. That is, when the brush 52 contacts with 30 the sector 49, the circuit from contact 57 extends through this brush, sector 49, commutator contact 46, brush 53, to contact 59. However, when the brush 52 is in contact with the commutator contact portion 44, the brush 53 is inactive since 35 the contact portion 44 is grounded through the shaft 35 and thence through the frame parts, or if desired, through a grounding spring contact as at 63 slidably engaging the top of the shaft in a manner hereinafter explained in connection with the description of the indicator supporting frames.

The indicator units may therefore be operated as follows: The circuit of contact 58 may be impulsively energized, a return circuit being provided through the ground connection. However, when a sufficient number of impulses have occurred to move the drum 20 and the commutator 41 to a predetermined "normal" or zero position, the ground return circuit will be removed by 45 reason of the contacting of the brush 52 with the sector 49. That is, the sector 49 may be positioned at such an angle in respect to the shaft 35 that when either a blank space or a desired normal position character is exhibited on the 50 drum through the window 21, the sector will come into engagement with the brush 52, and thus open the grounded impulsing circuit and automatically stop the stepping movement of the drum at the predetermined desired position. The drum may 55 then be advanced from this position only by energizing the circuit of contact terminal 59 with an impulse which will serve to advance the commutator and drum one step and restore the brush 52 into contact with the grounded contact member 44. Thereafter a sufficient number of impulses may be transmitted through the contact terminal 58 and the grounded return circuit, to 60 advance the drum 20 to exhibit the desired new character. With this method of operation, a plurality of the indicator units may be readily restored to "normal" by a single impulse transmitter and each unit will automatically stop its stepping movement when it arrives at the desired 65 normal position. Thereafter each of the units

thus "restored" may be advanced independently to the desired new positions.

These indicator units may be readily mounted in frame members as shown in Fig. 1 so as to be quickly slid into place or removed from the front 5 of the frame. The contact terminals 58 and 59 and also the grounding contact 63 provide quick-detachable connections cooperating with suitable contacts on the frame, as will be hereinafter described. 10

The lower frame portion 25 may be provided with lugs as at 64 struck outwardly and downwardly at a suitable angle to cooperate with guiding means in the supporting frame. At the front of the indicator unit the top and bottom frame 15 portions may be secured in respect to each other by corner posts as at 65. A suitable mask as at 66 may be provided with spring flanges 67 at its edges for detachably engaging the posts 65. The window or opening 21 above referred 20 to, may be provided in the mask 66, and as shown the drum is located so as to protrude slightly into the opening 21, thus clearly revealing the character to be exhibited but coming into close proximity of the edges of the opening so as to 25 substantially completely shield the adjacent characters from observation even though the adjacent characters may directly adjoin the character to be exhibited.

The top frame portion 22 may be cut away as 30 at 68 to provide easy access to the clamping screws 56 and associated parts. The rear frame portion 24 may be likewise cut away at this region for the same purpose and to permit the contact terminals to protrude. 35

It will be observed that the upper and lower edges of the armature 28 extend into close proximity of the upper and lower frame portions. Also the upper and lower frame portions may have inwardly struck lugs or ridges 70 and 71 40 respectively positioned directly above and below the end of the magnet core and in a generally parallel relationship with the upper and lower edges of the armature 28 and co-extensive therewith. The frame member, being of suitable magnetic material, may therefore provide an efficient magnetic return circuit cooperating with the armature and the magnet pole piece with substantially the shortest possible airgaps for constructions of this class. Also the ridges or 45 lug portions 70 and 71 make it possible for the magnetic airgaps between the armature and the frame portions, to extend in the general direction of movement of the armature and therefore the magnetic flux in these gaps cooperates with 50 the flux between the armature and magnet pole piece to efficiently operate the armature. 55

It is desirable to so position the contact sector 49 in respect to the starwheel teeth that the circuits of the brush 52 will never be broken at 60 the brush when the magnet is energized, but will be broken when the drum is under the control of the retracting spring 31. In this manner the breaking of the actuating current at the commutator may be avoided with the consequent 65 elimination of arcing.

The operating parts when constructed in the manner above described may be accurately duplicated at a very low cost, as is commercially desirable, in view of the large number of units necessary, for example, in broker's indicating boards. With indicator drums of suitable size for brokers' boards and light in weight, the stepping movement may be sufficiently rapid to accurately follow impulse frequencies of 20 to 30 per second 70 75

or frequencies of the order of magnitude of commercial alternating current lighting circuit frequencies, if necessary.

The indicator section frames as shown in Figs. 5 1 and 2 will now be described in further detail. These frames may comprise upright members as at 72 located between the indicators for each 10 stock or other quotation. If desired, a double upright member as at 73 may be provided at the 15 ends of the sections. At the top and bottom of the sections these uprights may be interconnected by suitable horizontally extending angle irons as at 74 and 75. It will be observed that five horizontal shelves as at 76 are provided between 20 each pair of uprights. Each of the lower four of these shelves is adapted to slidably receive four indicator units, that is, provision is made for a total of 16 indicator units in all for each stock, the quotations of which are to be posted. 25 The first, second, third and fourth shelves respectively provide space for the "last", "low", "high" and "opening" price quotations.

If desired, the hundreds digit indicator for the "high", "low" and "last" quotations may be omitted with a substantial saving in expense. In that event, the hundreds digit indicator of the "opening" price quotation will indicate to the observer the proper hundreds digit for the "high", low" and "last" prices or items. When these hundreds digit indicators are omitted, the spaces therefor may be filled with dummy boxes or if desired, a special form of indicator may be inserted in one of such spaces and arranged to give signals as to the prevailing activity of the 30 market in the particular stock or other item in question. For example, in lieu of the hundreds digit indicator for the "last" quotation, an indicator unit as above described might be inserted having a dial bearing a series of different colored areas. Thereby such indicator unit may be operated step-by-step until a colored area is exhibited corresponding to the degree of activity of the market, assuming that a predetermined arbitrary color scale has been adopted for such 40 purpose. The fifth or upper shelf 76 may provide a support for a multicontact relay as at 77, the function of which will be hereinafter explained, and also any other relays that may be there required for the operating circuits. It will be observed that each shelf is provided with four raised seating areas respectively for the four indicator units, these seating areas being interspaced with channelways as at 78 which are designed to be engaged by the guide lugs 64 formed 50 on the indicator units as above described. Also, upon each of the four lower shelves groups of insulated female contact members as at 79 may be provided for engagement with the quick-detachable indicator unit terminal contacts 58 and 55 60 59 above described. The grounding contact 63 is also shown as mounted upon the lower surfaces of each of the four upper shelves. The shelf areas are preferably covered with layers of sound deadening material such as felt, as shown at 76'. 65 With the above described frame construction, each of the indicator units may be readily slid into or out of the frame independently of the others to facilitate inspection, repair or replacement. In Fig. 2 it will be observed that the multicontact relay 77 is provided with a large plurality of terminal contacts as at 80. Two pairs of contacts 81 and 82 are mounted as shown upon the top of the section frame for alternative cooperation with the contacts 80. To shift the relay 70 75 from contacts 81 to contacts 82, it is merely nec-

essary to slide the relay along guideways as at 83 to the position indicated by dotted lines in Fig. 2. Additional groups of section terminal contacts may be provided at 84 at the top of the section. The purpose of these numerous contacts 5 will be explained hereinafter in connection with Fig. 8.

A plurality of the section frames as of Figs. 1 and 2 may be arranged to form a broker's board in the manner shown in Fig. 9. That is, the section frames may be arranged in a plurality of tiers. The various tiers may be separated by channel members or by spaced-apart uprights. The electrical connections as at 87 to the various sections may be located between these uprights 15 so as to be accessible from the front of the apparatus. These spaces may be covered by detachable vertically extending cover plates 88. The uprights may be secured to a suitable base member or frame as at 89. The indicator section 20 frames may be supported from the uprights at the desired elevations by brackets as at 90. The sections of each tier are preferably separated by horizontally extending spaces as at 91 for receiving the electrical connections to the various indicator section contacts. The group of indicator units and associated parts for each separate stock or other item may be covered by removable cover plates as at 92 having apertures as at 93 for exhibiting each of the four quotations for the stock. 30 It will be observed that elongated cover plates are provided at 92' to cover the spaces 91 so as to give the entire structure a finished appearance. Cover plates 92 and 92' also provide space for number cards showing yesterday's quotations 35 and other information. The electrical connections to the above described apparatus will now be explained.

Fig. 8 shows the circuit connections for the quotation indicators for two stocks or other items on a broker's board. That is, the connections for a total of 32 indicator units are shown. The magnets 26 and parts of the commutator 41, namely the contacts 44, 45 and 49, as well as the terminal contacts 58, 63 and 79 as above described, are all diagrammatically shown. It will be observed that the multicontact relays 77 as above referred to are each provided with seventeen contacts, sixteen of which as at 94 respectively are individually electrically connected through corresponding contacts 79 to each of the indicator terminal contacts 58 of one stock. The seventeenth contact on the multicontact relays, designated by the numeral 94', is electrically connected to all of the indicator contact terminals 59 of the corresponding stock by means of connection wires 95. It will be observed that seventeen of the relay terminal contacts 80 are provided for alternatively engaging a corresponding number of the stationary contacts 81 or 82. The contacts 81 may be connected by bus wires as at 96 to a corresponding number of section terminal contacts 84 as above referred to. The contacts 82 may likewise be connected by bus wires as at 97 to a corresponding number of section terminal contacts 84'. The contacts 84 in turn are each connected to the operating busses 98 of one transmitter equipment, whereas the contacts 84' respectively may be connected to operating busses 99 of a duplicate transmitter equipment. That is, the indicators for each stock may be controlled over either the busses 98 of one system or channel, or over the busses 99 of a duplicate system or channel. To shift the indicators from one system or channel to another, 70 75 80 85 90 95 96 97 98 99 100

it is merely necessary to slide the relay 11 in the manner above described into proper position, so that its terminals 80 contact either with the terminals 81 or terminals 82, as desired. The relays 11 are normally in open circuit condition, as indicated in Fig. 8, so that the circuits to all of the indicator units are normally open. For each stock a pair of selector wires as at 100 and 101 are provided, and the same may run to an interchangeable plug terminal board such as disclosed in the copending applications above referred to, and thence to suitable selector equipment. In order that the selector wire 100 may be normally in open circuit condition, a relay 102 may be provided in circuit with the selector wire 101 for controlling a normally open contact 103. When selector wire 101 is energized through relay 102 and a ground return as shown, the contact 103 will be moved to circuit closing position, whereupon if the selector wire 100 is also energized, its circuit will be completed through the relay 11 and a ground return. The multicontact relay will thereupon "pick up" and connect the indicator operating circuits to the control busses through the seventeen contacts 94 and 94'. Meanwhile, however, all of the other multicontact relays on the broker's board may remain in open circuit position so that the connections thereto will not interfere with those of the indicators for the particular selected stock. In the copending Haselton applications above mentioned, means are disclosed whereby any desired pair of selector wires as at 100 and 101 may be selectively and conjointly energized, thereafter groups of operating impulses being transmitted over operating busses such as indicated at 98 and 99. The selector wires 100 and 101 may be connected through section terminal contacts as at 84" to selector cables as at 104. All of the cables or wires 98, 99 and 104 may extend to a selector cabinet. The contacts 81 and 82 respectively may be interconnected to corresponding contacts for other stocks or items by "jumper" cable connections as at 106 and 105.

45 While circuit connections are shown in Fig. 8 for only two stocks, it will be understood that the connections may be extended in a similar manner to the indicator units for many additional stocks or items. Indicator units for ten different stocks may be conveniently arranged in each frame section and a sufficient number of frame sections may be provided with each installation to exhibit the quotations for all stocks which are of particular interest to a broker or his customers.

55 It will be understood that any of the other various types of indicator units known in the art and suitable for the purpose may be employed instead of the type of indicator above described.

60 While the invention has been described in detail with respect to a certain preferred example thereof which gives satisfactory results, it will be understood by those skilled in the art after understanding the invention, that various changes and modifications may be made without departing from the spirit and scope of the invention and it is intended therefore in the appended

claims to cover all such changes and modifications.

What is claimed as new and desired to be secured by Letters Patent of the United States is:

1. An indicator board comprising a plurality of sections each receiving a plurality of interchangeable electromagnetically operated indicator assemblies and each providing a receptacle to receive a relay assembly including a multicontact switch member connected to control wires 10 leading to the associated indicator assemblies, a plurality of series of contacts carried by each section accessible within said receptacle, and a relay assembly including a multicontact switch member in each receptacle, said relay assembly 15 including a series of contacts for connection with any of said plurality of series of contacts on the section, said relay assembly and section having means facilitating movement of said switch member to selectively connect its series of contacts 20 with any of the plurality of series of contacts on the section.

2. An indicator board comprising a plurality of sections each supporting a plurality of electromagnetically operated indicator assemblies and 25 each providing a receptacle to receive a multicontact switch member connected to control wires leading to the associated indicator assemblies, a plurality of series of contacts carried by each section accessible within said receptacle, and a multicontact switch member in each receptacle having a single series of contacts for cooperating with any of said plurality of series of contacts on the section, said switch member and section having means facilitating movement of said switch member 30 to connect its single series of contacts with any of the plurality of series of contacts on the section.

3. An indicator board comprising a plurality of electrically operated indicator assemblies each 40 individual to a stock or item for posting quotations or other information in regard thereto, each such indicator assembly including switching means comprising a mounting member carrying contact means for electrically connecting the operating circuit to any of a plurality of different quotation transmitting channels for receiving signals from the selected channel, a plurality of series of contacts respectively associated with said transmitting channels, and slidable supporting 50 means for said mounting member whereby the contact means carried thereby may selectively be slid into circuit closing engagement with any of said series of contacts of the different transmitting channels whereby said indicator assemblies 55 may be grouped in any desired manner for operation from said transmitting channels.

4. An indicating device comprising a plurality of groups of electromagnetic indicator units, multicontact relays having terminals for controlling the circuit connections of each group respectively, duplicate systems of control busses for cooperating with said relays, and slidable supporting means for said relays whereby the relay terminals may be slid into engagement with connections to either of said bus systems alternatively. 65

MERTON L. HASELTON.
